UNITED STATES PATENT OFFICE.

SAMUEL E. DAVIS, OF JOLIET, ILLINOIS, ASSIGNOR OF ONE-HALF TO
EDWARD A. BOAZ, OF SAME PLACE.

FIRE-ESCAPE LADDER.

SPECIFICATION forming part of Letters Patent No. 296,145, dated April 1, 1884.

Application filed June 6, 1883. (No model.)

To all whom it may concern:

Be it known that I, SAMUEL E. DAVIS, a citizen of the United States of America, residing at Joliet, in the county of Will and State of Illinois, have invented certain new and useful Improvements in Fire-Escape Ladders, of which the following is a specification, reference being had therein to the accompanying drawings.

10 Figure 1 is a side elevation. Fig. 2 is a side view of the ladder when folded and down on the ground; Fig. 3, a side view of the upper end of the ladder disconnected, with the window-sill grapple; Fig. 4, a side view of the 15 ends of two of the sections of the ladder, showing how they hinge together, and extended and locked open; Fig. 5, a similar view of two sections folded together and locked; Fig. 6, a perspective view, showing 20 the manner of attaching the rounds to the folding bar, and also the manner of attaching a supporting cord or wire to sustain the outer ends of the rounds; and Fig. 7, a face or front view of the hook on the upper end of 25 the ladder, showing it divided in two parts or prongs, and having rollers in each prong to roll against the side of a building.

This invention relates to certain improvements in fire-escape ladders, and is of that 30 class that are intended to be portable and folding, so as to be extensible by unfolding to any desired height, and intended to be used to extend up to the windows or any place on a burning building, to enable persons to escape or firemen to ascend.

Referring to the drawings, H represents the folding bar, made in sections and having each section hinged together by the hinges B, so it will extend, as shown in Fig. 1, or fold up, 40 as shown in Fig. 2. The bar is provided along up each side with rounds D, which may be attached to it by being pivoted thereto, as shown in Fig. 3, or attached permanently, as shown particularly in Fig. 6, by means of their flared inner ends being inclosed by the collar d, which screws to the side of the bar H. The outer ends of the rounds D are supported by a strong cord or wire, w, which may be attached to the rounds by passing through a 45 slit, v, as shown in Fig. 6, and taking a turn or so around the end of the round to support

the round, or it may have knots, as shown at w² in Fig. 3, upon which the rounds can rest, if desired. In either case the wire w attaches at its upper end to the bar H, as shown in 55 Figs. 1 and 3, so as to hold the rounds from falling below a level at their outer ends. Brace-wires w³ serve to stiffen the ladder laterally by acting as a bridging when the ladder is extended, as shown in Fig. 3. When the 60 wire w is provided with the knots w², it passes through the end of each round loosely through a loop, and when the ladder is taken down to be folded the wire w is loosened at the bottom, so the rounds can fold upward, as shown in 65 said Fig. 3, by permitting the wire w to slide in the loop in the ends of the rounds. The wire w is provided along its length with hinges w', or, in other words, is cut in sections and looped together at w', so it will fold 70 with the bar H, the loops w' being opposite the hinges B of the bar H, as shown. The brace-wires w³ loop over the wire w, so it can slide along on said wire above the knots w², to assist in folding or extending the bar H. The 75 upper end of the bar H terminates in a grappling-hook, a, to hook into a window, or on any object after the ladder is extended. This hook a may terminate in two hooks or prods, as shown in Fig. 7, and be provided with rollers h, to roll up against the side of a building.

The means for locking each section of the bar H to hold them extended, and so they may not fold up when not desired, is shown in Fig. 5. The latch B² is pivoted into the corner of one 85 section at B³, and has a flattened surface engaging with a spring, z, contained within the section; so that its resiliency will hold the latch either extended or closed. To hold the bar H extended, the latch catches into the notch 90 B⁵, as shown in Fig. 4. To hold the bar H folded, it will catch into the notch B⁴, as shown in Fig. 5.

For the purpose of more securely holding the upper end of the ladder into a window, it 95 is provided at its upper end with the apparatus shown in Fig. 1. A horizontal bar, s, is pivoted to the upper end of the upper section of the bar H, to which are attached two vertical bars, t and t', which slide along on the bar s 100 by means of said bar s passing through mortises in their upper ends. These two vertical

bars t and t' each terminate at their lower ends in hooks or grapples P and P' , pointing horizontally toward each other, and are drawn toward each other by the resiliency of the coil-spring s' , which connects them at their upper ends immediately beneath the bar s , a cord, c , running from the ground up along the bar H , through eyes i , along its length over a pulley, R' and R , and finally through the eye i' on the bar t' , and attaches to the pawl P^2 , pivoted on the side of bar t' , so its upper or outer end can engage with a ratchet along on the under side of the bar s . A pull on the cord c will elevate the outer end of lever s by means of the lever a' , pivoted on the side of the bar H , so its outer end rests against the under side of said lever s and its outer end attached to the cord c . Also, the cord c will pull down on ratchet or pawl P^2 and release it from the ratchet on the under side of bar s , so said cord can pull the bar t' back far enough so the space between bars t and t' will be wide enough so they will inclose the sill s^2 of the window. By releasing the tension on cord c the spring s' will draw the two bars t and t' together, so their prods P and P' will grapple over the window-sill to hold the upper end of the ladder up to the window, (as shown in Fig. 1,) so that ingress and egress at a window may be had at any story of a building in a very few minutes after an alarm of fire.

This attachment can be taken off and the ladder used with only the hook a when desired.

When it is desired to extend the ladder to a considerable height the pivoted rounds D , as shown in Fig. 3, may be used on either side

of the bar H , either single or double, in which case they act as a truss to strengthen the ladder laterally, so it can be raised without fear of its swaying or bending sidewise. When used double, a double set of supporting-wires may be used. In such case the pivoted rounds and wires will fold close to the bar H , so as to be out of the way when folding the ladder, as shown in Fig. 2.

Having thus described my invention, what I claim as new, and desire to secure by Letters Patent, is as follows, to wit:

1. The combination of the folding bar H , rounds D , wire w , and hook a , all adapted to operate as and for the purpose set forth.
2. The combination of the folding bar H , rounds D , cords w , having knots w^2 , and loops w' , locking-latch B^2 , and hook a , all adapted to operate as and for the purpose set forth.
3. The combination of the bar H , cord c , pivoted bars s , vertical sliding bars t and t' , having the prods P and P' , and pawl and ratchet P^2 , all adapted to operate as and for the purpose set forth.
4. In the fire-escape ladder described, the cord c , adapted to extend the bar s , and separate the grappling-bars t t' , in the manner and for the purpose set forth.
5. The combination of the folding bar H , bar s , cord c , and grappling-bars t t' , having the hooks P and P' , all adapted to operate as and for the purpose set forth.

SAMUEL E. DAVIS.
